J. B. MELL.

Shovel-Plow.

No. 14,288.

Patented Feb. 19. 1856.

UNITED STATES PATENT OFFICE.

JAS. B. MELL, OF RICEBOROUGH, GEORGIA.

IMPROVEMENT IN PLOWS.

Specification forming part of Letters Patent No. 14,288, dated February 19, 1856.

To all whom it may concern:

Be it known that I, JAMES B. MELL, of Riceborough, in the county of Liberty and State of Georgia, have invented certain new and useful Improvements in Plows; and I do hereby declare the following to be a full, clear, and exact description of the same, reference being had to the accompanying drawing, in which—

Figure 1 represents a perspective view of the plow complete, in which similar letters denote like parts.

The nature of my invention relates to an adjustable standard and beam, hereinafter described.

To enable others skilled in the art to make and use my invention, I will proceed to describe the same with reference to the drawings.

A represents the standard of the plow; F, a slot near the upper end of standard A; C, a curved brace; K, notches on the under edge of curve-brace C, that fit inversely with the lower edge of slot F; I, a wedge placed in slot F to secure brace C with standard A; B B, braces attached to standard A; D, the plow-beam, hinged to braces B B by means of bolt z; N, a hook on the end of beam D for attaching a single-tree; W, a clasp on the lower end of brace C for hinging beam D at O by means of bolt X, to allow the beam D to work up and down; Q, a plow; T, a bolt for attaching plow

Q to standard A; H, handles of any desired form; G, the band for securing handles H to brace C by means of wedges y y; L L, braces bolted to the end of curved brace C at R, to govern the height of handles H by varying their length; M, a bar, with shoulders at e', for allowing braces L and handles H to be firmly secured by nuts V.

The operation will be obvious from the description, and a plow of any desired form can be worked to advantage on this standard by removing the wedge I and placing the standard A forward or backward on brace C, as the plow may be required to run deep or shallow. Driving the wedge I firmly in front of standard A, the handles only, being attached to brace C, change position as to height very slightly, and give the plowman the advantage of leverage when deep plowing is required.

Having thus fully described the nature of my invention, what I claim therein as new, and desire to secure by Letters Patent, is—

The standard A, with braces B, in combination with braces L C and beam D, constructed in the manner and for the purpose set forth.

JAMES B. MELL.

In presence of—

W. L. WALTHOUR,
W. B. FLEMING.
